CHARLES J. ROBERTSON, OF TAUNTON, MASSACHUSETTS, ASSIGNOR TO THE MIEHLE PRINTING PRESS & MANUFACTURING COMPANY, OF CHICAGO, ILLINOIS, A CORPORATION OF ILLINOIS.

BED-MOTION FOR PRINTING-PRESSES.

1,193,719.

Specification of Letters Patent.

Patented Aug. 8, 1916.

Application filed March 25, 1914. Serial No. 827,040.

To all whom it may concern:

Be it known that I, CHARLES J. ROBERTSON, a subject of the King of England, residing at Taunton, in the county of Bristol 5 and State of Massachusetts, have invented certain new and useful Improvements in Bed-Motions for Printing-Presses, of which the following is a specification.

The invention relates to mechanism for 10 converting rotary motion into rectilineal reciprocating motion, and is particularly designed for use in connection with the reciprocating beds of printing presses, though it may be applied and used in any location and 15 for any purpose for which the same is adapted.

In order that the principles of the invention may be fully apparent, I have herein disclosed for illustrative purposes one embodiment of the invention in the accompanying drawings, it being understood that the invention may be carried out by other embodiments thereof and by mechanism widely differing from that herein selected for illustration.

In the drawings: Figure 1 is a vertical longitudinal section on line 1—1 of Fig. 2 of a single impression cylinder and a bed co-operating therewith and operated in accordance with my invention; and Fig. 2 is a vertical transverse section along the line 2—2 of Fig. 1 of the type of operating mechanism herein selected for illustration, the reversing shaft and its outer gear being indicated in elevation, and the impression cylinder and the driven gear carried thereby being diagrammatically indicated by dotted lines.

As shown, the bed of the printing press is constructed in any suitable manner and operatively connected to mechanism to cause the continuously and uniformly running shaft, first to propel the bed continuously and at uniform speed in one direction, and then to propel the bed continuously and at uniform speed in the opposite direction, and also to provide for the reversal movement of the bed at the ends of its continuous and uniform movement in each direction by gradually slowing down said movement until the bed is brought to rest and then gradually accelerating its movement in the opposite direction until it acquires the speed of its uniform stroke.

In the usual operation of a printing press of the bed and cylinder class, the bed carrying the type or other printing form is reciprocated in the manner above stated, the peripheral impression surface of the cylinder and paper thereon traveling in the printing operation at the same surface speed as the form on the bed, so that the paper is pressed against the surface of the form with a rolling action and without any slip of one surface relative to the other along the line of contact between the cylinder and bed. In this class of press the impression is commonly taken only in the travel of the bed in one direction under the cylinder, which continues to run in the same direction all the time that the press is in operation, and after the bed has made its forward and working movement or stroke under the cylinder, the bed must be returned past the cylinder to the starting point preparatory for another working stroke. In the return movement of the bed the cylinder is commonly raised a little so that its surface is entirely above and clear of the form on the bed, which is now traveling in an opposite direction to the surface of the cylinder, which thus makes an idle revolution during the return or non-working stroke of the bed. Generally speaking the mechanism for driving the bed of such class of printing presses comprises a continuously rotating toothed gear and two racks connected with the bed so as to be positioned adjacent opposite edges of the gear and means to cause engagement of one of the racks with said gear to produce the principal part of a stroke in one direction, and to cause the engagement of the other rack with the gear to produce the principal part of the stroke in the other direction, the bed commonly running at uniform speed throughout the part of its stroke effected by the rack and gear, this being the same as the surface speed of the cylinder during the stroke. When the bed arrives at the end of such rack and gear movement, it comes under the control of another part of the bed motion, which may be termed the reversing mechanism, and which acts to bring the bed to a stop at the end of a short movement beyond the rack traveling movement, and to start the bed in the reverse direction and bring it to the velocity of the rack driven movement by the

time that the second rack arrives at and comes into engagement with the gear, at which time the reversing mechanism gives up control and the bed is again driven by the rack and gear movement to the point near the other end of its stroke, where the reversing mechanism again takes control and performs a similar reversal of the movement of the bed to that just described. That is to say, the reversing mechanism is designed to take the bed at full working speed, reduce its velocity by gradual diminution until it is stopped and then move it in the opposite direction with a gradual acceleration until it is brought up to full working velocity in said opposite direction. In such type of mechanism the gear and racks may be relatively shifted in many different ways so that the rack and gear meshing teeth used to move the bed in one direction while in action, are out of conflict when the bed is being driven in the opposite direction by the other rack and gear meshing teeth.

My invention is applicable to a gear and rack mechanism wherein the relative shifting of said gear and racks is accomplished by providing the bed with two down-facing racks placed side by side and by using therewith two oppositely rotated gears shifted into and out of the plane of action of each rack. The particular embodiment of this two gear and two rack device I have illustrated herein, is one in which the plane of engagement between the top of one gear and its rack is at a different clearance level from the plane of engagement between the top of the other gear and its rack, and one in which the racks are side by side spaced approximately the width of one rack between, and one in which the two gears, one double face and one single face, are constantly intermeshed, are simultaneously shifted transversely and in the same direction the one into and the other out of the vertical plane of its respective rack and vice versa, that gear which is double-faced meshing into that rack which is at the lower level.

In the drawings, the bed of the press is indicated at 1 and the impression cylinder at 2, said cylinder being driven in any preferred manner, such for example, as shown in Fig. 2, by a gear 3 at one end thereof, meshing with a gear 4, upon a reversing shaft 5, mounted in suitable bearings 6, 6, in the framework of the machine, said framework supporting therein tracks or ways 7, 8, 9, and 10, preferably having sets of rollers 11, 12, 13 and 14 receiving the bed 1.

The lower face of the bed 1 is provided with racks 15, 16, herein shown both down-facing and placed side by side, spaced at least slightly wider than the width of a single rack apart and with the teeth of rack 15 located in a higher horizontal plane than

those of rack 16 by an amount at least slightly greater than the working depth of the racks or gear teeth. Both of racks 15 and 16 are positioned above the single reversing shaft 5.

Concentric with the reversing shaft 5 is revolubly mounted the double faced bed reciprocating gear 18 of such diameter that, through the connecting gears 3, 4, the peripheral speed of bed reciprocating gear 18 is the same as that of the peripheral printing surface of cylinder 2. This double faced bed reciprocating gear 18 is constantly driven by a driving connection with reversing shaft 5 and is so positioned that its top will mesh into and drive rack 16 when shifted into the plane of said rack 16. Alongside the bed reciprocating gear 18 and intermeshed therewith is an oppositely rotating single faced bed reciprocating pinion 17, positioned so that its top may mesh into and drive rack 15 when shifted into the plane of said rack 15. As bed reciprocating pinion 17 is to rotate at the same peripheral speed as bed reciprocating gear 18 it is preferably directly intermeshed therewith as stated.

Since in the present embodiment of the invention said racks are shown fixed stationary upon the bed and the relative movement between each gear and its coöperating rack is obtained by a shifting movement of said gears, herein shown as a horizontal shifting movement, said gears 17, 18 are so mounted as to be brought alternately each into working relation with its respective rack, their respective axes being so positioned that the top of each gear is always in the proper working horizontal plane of the teeth of its respective rack.

In many presses where racks are employed whose teeth face each other, the lower rack has been arranged below the large bed reciprocating gear, so that said lower rack engages said gear at the lower edge of the gear. Such a construction is objectionable in that the moving weight on the bed of the press is largely increased by the down hanging length of the parts required to support the lower rack beneath the large bed reciprocating gear. Even in those presses where racks are employed whose teeth face each other, both racks passing above the reversing shaft, one of the racks still must be hung down below the bed reciprocating pinion and the support for the bed reciprocating pinion meshing into this hung rack is not easily made as rigid as desired. The use for the one stroke of the small additional oppositely rotating bed reciprocating pinion 17 with its solidly supported down-facing rack 15 instead of the usual lower rack hung below the large bed reciprocating gear, together with the usual use of the top of the large bed reciprocating gear 18 and its usual down-facing rack 16

for the other stroke, allows both racks to be closely held up to the bed instead of being hung down at a very considerable distance therefrom. Also this construction 5 allows the bed reciprocating pinion 17 to be solidly supported from the framework of the machine upon both its sides, the absence of down-protruding rack-hanging parts allowing this.

10 Power may be applied to the machine by many well known means, as for instance by a driving pinion upon a pulley shaft, said pinion (not shown) meshing into gear 4.

In the embodiment of the invention shown 15 the double-faced bed reciprocating gear 18 and the single faced bed reciprocating pinion 17, being shifted across from rack plane to rack plane, are shown intermeshed and are shown as being shifted in the same 20 direction at the same time; that is to say, as shown they are shifted together as one. In the middle of the double width of the bed reciprocating gear 18, between the two working faces thereof, is an annular groove 25 19 and on one side of the single face of bed reciprocating pinion 17 is fixed a disk 20 which takes into the groove 19 and causes bed reciprocating pinion 17 to shift when bed reciprocating gear 18 is caused to shift. 30 The bed reciprocating pinion 17 is here shown mounted to rotate and slide freely upon a fixed stud 21, which stud may be securely fastened upon each side of pinion 17 to the framing of the machine for instance to tracks 8, 9. It is evident many 35 different ways of shifting these two gears 17, 18 may be used. When the disk 20 and groove 19 are used to connect them, it is apparent that racks 15, 16 will need to be 40 spaced apart an amount at least slightly greater than the sum of one rack width plus twice the thickness of disk 20, all as shown. Bed reciprocating gear 18 is mounted to revolve with and be directly driven by the 45 reversing shaft 5, being positioned concentric to reversing shaft 5 by the drum-like support 22, upon which the bed reciprocating gear 18 is adapted to be shifted by sliding thereupon, axially to itself. The support 22 may rotate with the reversing shaft 5, in which case the driving feathers 23 may be fixed or integral (as shown) with support 22 and the bed reciprocating gear 18 would merely slide axially upon and in relation to 55 support 22 when shifted. Again the support 22 may be fixed to bearing 6, in which case the driving feathers 23 would be fixed to reversing shaft 5 or to its crank arm or disk 24 and the gear 18 would rotate upon 60 and not with support 22 and when shifted would therefore slide helically upon and in relation to support 22 but axially as to shaft 5, being guided thus by feathers 23.

Many ways of shifting bed reciprocating 65 gear 18 and pinion 17 may be used. The

means shown consist of a continuously rotated cam shaft 25, suitably supported in bearings in the framework and operatively connected to the rest of the machine to make one revolution for each complete movement 70 forward and back of the bed. A grooved cam 26 upon cam shaft 25 swings a double lever 27 by the action of a roll 28 in the cam groove. This double lever 27 may be fulcrumed at 29, 29 on the framework of the 75 press, and by means of pivoted tongue pieces 30, 30 entering groove 19 in gear 18 will act to shift bed reciprocating gear 18 and pinion 17 bodily together transversely to and fro into and out of the two vertical planes of 80 rack action; disk 20 upon pinion 17, entering groove 19 in gear 18 causing pinion 17 to shift as gear 18 is shifted as already pointed out.

During the engagement of the pinion 17 85 with its rack 15 and of the gear 18 with its rack 16, the bed 1 is driven at a uniform speed in one direction or the other. As the bed 1 nears the limit of movement in either direction, mechanism is brought into play 90 to control the movement of the bed 1 during the shifting of gear 18 and pinion 17 from one rack plane to the other, such mechanism preferably being such as to receive the bed 1 at its full speed of movement, gradually 95 to diminish such rate of speed until bed 1 is brought to a stop and then to drive the bed 1 in the opposite direction at a gradually increasing speed until the working speed of the bed is again brought under 100 the control of pinion 17 or gear 18 as the case may be.

In order to control bed 1 during the described shifting of bed reciprocating gear 18 and pinion 17 there is indicated for that 105 purpose in that embodiment of the invention herein shown, reversing gears 31, 31^a (Fig. 1) mounted one in each forked end of a slide bar or member 32 having a crosshead 32^a receiving therein the crosshead block 33 110 mounted upon the crank pin 34 projecting from the crank arm or disk or primary reversing element 24 on, and preferably forged or otherwise integral with the reversing shaft 5.

The forked ends of the slide bar or member 32 carry the reversing gears 31, 31^a which are constantly in reciprocating mesh with and are rotated by stationary reversing racks 35, 35^a suitably mounted upon the 120 framework of the press. The forked ends of the slide member 32 are out-turned and engage with suitable ways 36, 36^a at either side of the stationary racks 35, 35^a, thereby to steady the movement of said slide bar 32. 125

The bed 1 is provided with a short, downwardly facing reversing rack 37, (shown with the teeth removed from the central unused portion) with which the reversing gears 31, 31^a are alternately brought into en- 130

gagement by the rotation of reversing shaft 5 and crank pin 34 and the consequent sliding to and fro of slide member 32.

As the bed 1 nears its limit of travel to the right viewing Fig. 1, the bed reversing rack 37 is brought into engagement with the reversing gear 31, at which time the shifting of the bed reciprocating gear 18 and pinion 17 commences, the said reversing gear 31 being rotated because of its meshing engagement with the stationary reversing rack 35 and the crank arm connection with the reversing shaft 5. The said crank arm connection is such that under the control of said gear 31, the movement of the bed 1 to the right is gradually reduced to zero and then gradually augmented in the opposite direction until the full working speed of the bed 1 has been secured at which time the bed reciprocating gear 18 and pinion 17 have been shifted to bring bed reciprocating gear 18 into driving relation with rack 16 and bed reciprocating pinion 17 out of driving relation with rack 15, the bed 1 then passing from the control of reversing gear 31 to that of bed reciprocating gear 18. As the bed 1 nears the end of its movement in the opposite direction, a similar operation occurs through the instrumentality of the bed reversing rack 37, stationary reversing rack 35^a and reversing gear 31^a passing the control of bed 1 on the return stroke to bed reciprocating pinion 17 and rack 15. While one rack 37 (or two racks close end to end) on bed 1 is shown coacting with two reversing gears 31, 31^a on slide member 32, it is obvious these two portions of the bed reversing rack 37 could be sufficiently separated end from end to accommodate the stroke of bed 1 and slide member 32 in such a way that one reversing gear 31 on slide member 32 could co-act alternately with the two bed reversing racks.

It will be apparent from the above description that the press herein described has comparatively a small weight of parts reciprocated with the bed, that the plane of travel of such weight may be low down near the floor, and that such bed is free in large

measure from twisting strains while allowing the center stay of the frame work that extends across below the cylinder and which has to withstand the bending stresses of the impression to be of unusual height and stiffness. 50 55

Having thus described one specific embodiment of my invention, I desire it to be understood that although specific terms are employed, they are used in a generic and descriptive sense and not for purposes of limitation, the scope of the invention being set forth in the following claims. 60

I claim:

1. In a printing press, the combination of a bed, a down-facing rack for each direction of bed travel disposed at different clearance levels, a bed reciprocating gear for one direction, a bed reciprocating pinion oppositely rotated and eccentric to and geared with said bed reciprocating gear for the other direction, a connection between the gear and pinion coupling the same together against relative axial displacement, means to slide axially the gear and pinion to and fro together bodily as one, and bed reversing means, substantially as described. 65 70 75

2. In a printing press, the combination of a bed, a down-facing rack for each direction of bed travel disposed at different clearance levels, a bed reciprocating gear for one direction and having a peripheral groove; a bed reciprocating pinion, oppositely rotated and eccentric to and geared with said bed reciprocating gear for the other direction, a disk fastened to the pinion 80 and projecting peripherally therefrom into said groove, means to slide axially the gear and pinion to and fro together bodily as one, and bed reversing means, substantially as described. 85 90

In testimony whereof I have hereunto signed my name in the presence of two subscribing witnesses.

CHARLES J. ROBERTSON.
